UNITED STATES PATENT OFFICE

EDWARD JAMES MURPHY, OF FRAMINGHAM, MASSACHUSETTS

CALKING TOOL

Application filed February 11, 1930. Serial No. 427,561.

My invention relates to tools for tamping the calking hemp and lead into the joints of pipes. The prior practice has been to place the male end of a pipe section into the female end of another, stuff hemp or other packing material into the space between the flange of the female end and the adjacent wall of the male end, and then pour molten lead into the joint to seal the same. After the lead has been poured it is tamped to make a tight joint. In tamping the packing and lead it has heretofore been the practice to use a flat tool and first tamp the packing adjacent the inner pipe section and then tamp it adjacent the outer flange, or vice versa. This is a slow and tedious job and frequently results in an imperfect packed joint owing to slippage of the lead in tamping the same.

My present invention has for its object to provide a tool which will, at the same time, tamp the packing adjacent the inner and outer walls of the joint, making one operation do the work of the two operations heretofore required.

Further, it is an object to provide a calking tool of such form as to enable its striking end to be located sufficiently far from the pipe so that it can be struck by a hammer or mallet without the hammer or mallet coming into contact with the adjacent pipe, thus avoiding danger of displacing the pipe sections or getting them out of alignment.

Generally the invention comprises a calking tool having a bifurcated end, one furcation being adapted to impact the calking material adjacent the outer rim while the other furcation is adapted to impact the calking substance adjacent the inner pipe section.

Further, the invention has for its object to provide a tool of the character stated in which the furcations are self-adjustable to pipes of various sizes.

Other objects will in part be obvious and in part be pointed out hereinafter.

To the attainment of the aforesaid objects and ends, the invention still further resides in the novel details of construction, combination and arrangement of parts, all of which

will be first fully described in the following detailed description, then be particularly pointed out in the appended claims, reference being had to the accompanying drawings, in which:—

55

Figure 1 is a perspective view showing the invention in use.

Figure 2 is a detail horizontal section on the line 2—2 of Figure 1.

Figure 3 is a detail vertical section on the line 3—3 of Figure 1.

Figure 4 is a side elevation of the tool.

Figure 5 is a front elevation of the tool.

Figure 6 is a rear elevation of the tool.

Figure 7 is a lower end view of the tool.

65

In the drawings, in which like numerals of reference indicate like parts in all of the figures, 1 represents the female end of a pipe section, and 2 represents the male end of another section, the former having the bowl 3 to receive the calking hemp 4 and the sealing lead 5.

The tool which constitutes my invention comprises a handle 6 and an off-set cylindrical body 8 connecting with the handle by a connection 7, the parts 6, 7 and 8 being integrally formed. The cylindrical portion 8 is slotted at 9 to receive the cylindrical portion 15 of the hinged leg 13 of the tool.

Integral with the body 8 is the fixed calking leg 10, the latter having a bevelled end 11 while the leg 13 has a bevelled end 14, the bevels 11 and 14 being oppositely directed. Furthermore the leg 13 is not located in a plane parallel with the leg 10 but at a slight angle thereto as indicated in Figure 2 of the drawings so that the leg 13 may lie against the pipe section 2 and the leg 10 may lie against the flange of the bowl 3. When so positioned the bevels 11 and 14 will provide

for the sharp edges of the legs to lie adjacent the respective pipe sections, see Figure 3.

The body 8 is provided with a stop lug 12 to cooperate with the shoulder 21 of the leg 13 to limit the pivotal motion of the leg in one direction. The leg 13 continuously tends to assume a position with the shoulder 21 against the stop 12 because of the provision of an abutment 16 on the cylindrical

eye portion 15 of the hinged leg 13, which abutment is engaged by a push pin or plunger 22 held in a recess 23 in the connecting part 7 of the tool, in which recess is also located a push spring 24.

17 is a hinge pin which passes through the hinged apertures 18 of the elements 8 and 15 and has its head 19 countersunk within the element 8, a cotter pin 20 holding the hinge pin 17 in place.

In using my invention the calking tool is positioned as indicated in Figure 1 with the leg 13 pressing against the pipe section 2 and the leg 10 pressing against the flange of the bowl 3. The legs are held against the respective pipe sections by virtue of the spring plunger 22 pressing the lug 16. Having positioned the tool as shown in Figure 1, the calking operation is accomplished by tapping the end of the handle and at the same time working the tool around the pipe 1, thus at one and the same time impacting the calking material or sealing material both adjacent the pipe section 2 and the flange of the bowl 3 of the pipe section 1.

From the foregoing description, taken in connection with the accompanying drawings, it is thought the complete construction, operation and advantages of my invention will be clear to those skilled in the art to which it relates.

What I claim is:

1. A calking tool comprising a body having a rigid impacting handle and a furcated impacting end, one of the furcations being rigid with the handle and the other being hingedly connected thereto.

2. A calking tool comprising a body having a rigid impacting handle and a furcated impacting end, one of the furcations being rigid with the handle and the other being hingedly connected thereto, and yielding means for holding said furcations in a separated position.

3. A calking tool comprising a body having a hinged portion, an impacting leg rigidly extending therefrom in one direction and a rigid impacting handle extending therefrom in the opposite direction, a second impacting leg having a hinge portion, means hingedly securing said hinge portions together, stop means limiting the movement of the hinged leg in one direction, and spring means acting yieldably to force said hinged leg in said one direction.

4. A calking tool comprising a rigid body having a hinged portion, an impacting leg rigidly extending therefrom in one direction, and an off-set handle extending therefrom in the opposite direction, a second impacting leg having a hinge portion, means hingedly securing said hinge portions together, stop means limiting the movement of the hinged leg in one direction, and spring means acting

yieldably to force said hinged leg in said one direction.

5. A calking tool comprising a body having a hinged portion, an impacting leg rigidly extending therefrom in one direction and a handle extending therefrom in the opposite direction, a second impacting leg having a hinge portion, means hingedly securing said hinge portions together, stop means limiting the movement of the hinged leg in one direction, and spring means acting yieldably to force said hinged leg in said one direction, said legs having oppositely directed end bevels.

6. A calking tool comprising a body having a hinged portion, an impacting leg rigidly extending therefrom in one direction and a handle extending therefrom in the opposite direction, a second impacting leg having a hinge portion, means hingedly securing said hinge portions together, stop means limiting the movement of the hinged leg in one direction, and spring means comprising a spring-pressed plunger carried by said body and a lug carried by the hinged portion of said hinged leg to cooperate with said plunger.

EDWARD JAMES MURPHY.
